UNITED STATES PATENT OFFICE.

JOSEPH P. MAXFIELD, OF MAPLEWOOD, NEW JERSEY, ASSIGNOR TO WESTERN ELECTRIC COMPANY, INCORPORATED, OF NEW YORK, N. Y., A CORPORATION OF NEW YORK.

VIBRATING SYSTEM.

Application filed August 28, 1917. Serial No. 188,582.

To all whom it may concern:

Be it known that I, JOSEPH P. MAXFIELD, a citizen of the United States, residing at Maplewood, in the county of Essex and State 5 of New Jersey, have invented certain new and useful Improvements in Vibrating Systems, of which the following is a full, clear, concise, and exact description.

This invention relates to diaphragms, and 10 more particularly to phonographic diaphragms such as those used in phonographic recorders and reproducers.

The object of this invention is to provide 15 a diaphragm which will be more sensitive to a wider range of frequency than those heretofore employed. A specific object is to construct a diaphragm having both a low natural frequency and a high natural frequency.

20 Although this invention will be herein-after described in connection with a phonographic reproducer or sound box, it is not limited to such an application, but may be employed in connection with any suitable 25 sound recording, transmitting or receiving device in which a vibrating member may be included.

It is well known in the art that a dia- 30 phragm clamped at its edges, as in a sound box for a talking machine or in a telephone transmitter, for example, does not respond equally for all frequencies of vibration im- 35 pressed upon it, but for each diaphragm there is a frequency in the neighborhood of

40 which there will be maximum response, and for other frequencies the response will be much less. The frequency for maximum response is generally known as the natural frequency of the diaphragm. The value of 45 this natural frequency for a diaphragm depends upon its elasticity or stiffness and mass, increasing with increase in elasticity, and decreasing with increase in mass. The amount of response for any given frequency 50 depends upon the friction, effective mass and the elasticity of the vibrating system.

For frequencies near the natural period the response is governed mainly by the friction, being larger the smaller the friction; 55 above the natural period the effective mass is the governing quantity, the response being larger the smaller the mass; while below

the natural period the elasticity is the most important factor and the response is greater the smaller the value of the elasticity.

Thus, if the diaphragm in a phonographic reproducer or recorder is of high elasticity and of small effective mass, it will give maximum response to high notes to the detriment of those of low frequency. On 60 the other hand, if the diaphragm has a low degree of elasticity and is of appreciable mass the low notes will be reproduced well, to the detriment of the higher tones.

This invention embodies a diaphragm of 65 such a character that it will reproduce efficiently notes of both low and high frequency. To accomplish this, the diaphragm is made non-uniform and capable of vibrat- 70 ing in two different ways. In the specific 75 embodiment hereinafter described in detail, the diaphragm consists of a central portion of a highly elastic material having a high natural frequency and an outer portion composed of a flexible membrane. When such a 80 diaphragm is clamped between suitable clamping arms and a stylus bar carrying the reproducing or recording needle is fastened to the central portion of the diaphragm and vibrations of low frequency are impressed 85 on the diaphragm, the entire diaphragm will undergo displacements on account of the low natural frequency of the outer portion. Of course, the natural frequency of vibration of the outer portion of the diaphragm 90 is lowered somewhat by the addition of the mass of the central portion, and is also modified to some extent by the fact that the central portion is connected to the stylus bar. The central portion on account of its 95 high natural frequency will not vibrate of itself, but will act as a plunger. When, however, the oscillations impressed on the diaphragm are of high frequency, the central portion, on account of its high natural 100 frequency, vibrates readily, while there is negligible motion of the rest of the dia- phragm. The response for frequencies intermediate between the two natural frequencies is made as large as possible by having the effective mass of the moving system reduced to as low a value as can be conveniently obtained. A diaphragm constructed in such a manner as above described therefore ef-

fectively responds to both low and high frequencies, as well as those intermediate in value.

For the better understanding of this invention, reference is made to the accompanying drawings, in which Fig. 1 represents a cross-sectional view of this invention as embodied in a phonographic sound box; Fig. 2 illustrates the top view of a portion of the same; and Fig. 3 is a cross-sectional view of a diaphragm.

In the embodiment of this invention illustrated in Fig. 1, 4 is a sounding box suitably fastened to the frame or diaphragm holder 5. A flange 6 of the frame serves to clamp the diaphragm 7 between two rubber gaskets 8 and 9. Upon the frame 5 is mounted a bracket 12, which, by means of the knife edges 13 (see Fig. 2), supports a socket 14 adapted to receive a stylus needle. The stylus bar 17 is fastened at one end to the socket 14 and at the other end is fastened to the central portion of the diaphragm 7. Suitable tension on the stylus and diaphragm is obtained by the springs 18 (see Fig. 2). Diaphragm 7 has an outer portion 19 of flexible material and a central portion 20 of a highly elastic material. The stylus bar 17 is shown attached to said central portion. If we assume that the stylus needle is impressing vibrations of low frequency upon the diaphragm, the whole diaphragm will undergo displacements on account of the low natural frequency of the flexible material which composes the outer part of the diaphragm. The stiff central portion 20 will not vibrate of itself but will act merely as a plunger attached to the stylus bar 17. When, however, the impressed vibrations are high, the stiff central portion will of itself undergo vibrations on account of its high natural period, while the displacements of the remainder of the diaphragm will be negligible. It has also been found, providing the stylus bar and the diaphragm are of minimum mass, that for vibrations of intermediate frequency between the two natural frequencies the diaphragm responds efficiently, although the response is not as great as for frequencies near one of the natural frequencies.

Fig. 2 shows more in detail the relation of the stylus bar to its supporting structure. The stylus bar 17 is shown to have two arms 25 and 26, which are pivoted on two knife edges 13, 13. The two tensioning springs 18, 18 extend from the bracket 12 to the arms 25, 26. Since the stylus bar and its supporting arms are also part of the moving system, it is preferable that the effective mass of the stylus should be as small as possible, for otherwise, as stated previously, the response for frequencies on either side of the natural frequency would be inefficient. It is, therefore, preferable that the stylus

bar should be made of some light material such as aluminum.

All of the above structure, except that of the diaphragm and the light mass stylus bar, is well-known in the art and is described merely to enable the application of this invention to be more readily presented.

Fig. 3 is a cross-sectional view of the diaphragm showing in detail its structure. 30 and 31 are two thin sheets of a flexible material, such as paper, cemented together near their outer edges. Between the two sheets, and suitably cemented together and to the paper sheets, are three discs 32, 33 and 34, of some suitable highly elastic material such as wood or steel, for example. It is preferable that the diameter of these discs should be from one-third to five-sixths of the diameter of the sheets of paper, although the ratio may have any suitable value, depending upon the material composing the discs and the other vibrating parts. The discs shown are made of wood and have their grains crossed in such a manner that warping is prevented. Any number of discs 80 may be used in order to obtain the desired stiffness; in the case of metallic discs only one would be necessary. It has been found convenient to use two sheets of paper and to cement the discs in between the sheets, but such an arrangement is not essential, as the discs may be cemented on the outside, in which case only one sheet of paper could be used. The membranes between which the discs are suspended may be of any suitable flexible material such as paper, oiled silk, or parchment. It is readily seen that such a diaphragm is not limited to the supporting structure illustrated in Fig. 1, as it may be used in connection with any sound box desired, or in connection with any suitable structure in which a vibrating member is employed.

What is claimed is:

1. A diaphragm comprising a plurality of wooden discs of approximately the same diameter and cemented together, a thin sheet of paper cemented to each side of said discs, said sheets extending beyond the edges of said discs and having their extending portions cemented together, the part of said diaphragm within the perimeter of said discs having a natural frequency of vibration corresponding to a high musical note.

2. A diaphragm comprising two flexible membranes cemented together, a disc of small mass suspended between said membranes, a part of said membranes extending beyond the perimeter of said disc and having a natural period corresponding to a low musical note and the portion of said diaphragm lying within the perimeter of said disc having a natural frequency of vibration corresponding to a high musical note, whereby said portion is adapted to vibrate.

- within itself substantially independent of the remainder of said diaphragm for vibrations of the natural frequency of said portion.
5. 3. A diaphragm comprising two thin sheets of paper cemented together, and a plurality of wooden discs between said sheets at their central portion adapted to act as a plunger when the whole diaphragm 10 is vibrating, the part of said diaphragm within the perimeter of said discs having a natural frequency of vibration corresponding to a high musical note.
4. A diaphragm having a natural period 15 corresponding to a low musical note and comprising a central portion of small mass and a flexible portion, said central portion having a natural period corresponding to a higher musical note and comprising a disc 20 of stiff, highly elastic material, and said flexible portion being of larger diameter than said disc and forming a flexible mounting for said disc.
5. A vibratory system comprising a stylus 25 bar and a diaphragm, the stylus bar and the diaphragm as a whole having a natural period corresponding to a low musical frequency, said diaphragm comprising a central portion of small mass and a flexible portion, said central portion having a natural 30
- period corresponding to a higher musical frequency and comprising a disc of stiff, highly elastic material, said flexible portion being of larger diameter than said disc and forming a flexible mounting for said disc, 35 the effective mass of the stylus bar and of the diaphragm each being small, whereby the system is highly responsive to musical frequencies other than said two musical frequencies. 40
6. A vibratory system comprising a diaphragm and having a natural period corresponding to a low musical frequency, said diaphragm comprising a central portion of small mass and a flexible portion, said central portion having a natural period corresponding to a higher musical frequency and comprising a disc of stiff, highly elastic material, said flexible portion being of 45 larger diameter than said disc and forming a flexible mounting for said disc, the effective mass of the system being small, whereby said system is highly responsive to musical frequencies other than said two musical frequencies. 50

In witness whereof, I hereunto subscribe my name this 23rd day of August, A. D., 55
1917.

JOSEPH P. MAXFIELD.
